DESIGN FOR A PICTURE-VIEWING CASE OR SIMILAR ARTICLE

Robert N. Dennis, Brooklyn, N. Y.

Application October 31, 1941, Serial No. 103,968

Term of patent 7 years

To all whom it may concern:

Be it known that I, Robert N. Dennis, a citizen of the United States of America, residing at Brooklyn, in the county of Kings, New York, New York, have invented a new, original, and ornamental Design for a Picture-Viewing Case or Similar Article, of which the following is a specification, reference being had to the accompanying drawing, forming part thereof.

Fig. 1 is a plan view of the picture-viewing case,

Fig. 2 is a side view of the same,

Fig. 3 is a front view thereof, all three views showing my new design in a closed position; and

Figs. 4 and 5 are side and front views corresponding to Figs. 2 and 3 respectively, but both showing the case opened for the purpose of viewing the picture.

I claim:

The ornamental design for a picture-viewing case or similar article, as shown.

ROBERT N. DENNIS.
